INVENTOR

UNITED STATES PATENT OFFICE

96,675

DESIGN FOR A SERVICE STAND FOR THE DISPLAY OF HORS D'OEUVRES

Louis Kessler, New York, N. Y.

Application June 24, 1935, Serial No. 57,375

Term of patent 3½ years

To all whom it may concern:

Be it known that I, Louis Kessler, a citizen or the United States of America, residing in Manhattan, county of New York, and State of New York, have invented a new, original, and ornamental Design for a Service Stand for the Display of Hors d'Œuvres, of which the following is a specification, reference being had to the accompanying drawing, forming part thereof, wherein.

A feature of my design resides in the bell inside the service stand.

I claim:

The ornamental design for a service stand for the display of hors d'œuvres, substantially as shown and described.

LOUIS KESSLER.
